REGISTERING MECHANISM FOR PRINTING CYLINDERS

William F. Huck, Richmond Hill, N. Y., assignor
to R. Hoe & Co., Inc., New York, N. Y., a cor-
poration of New York

Application September 10, 1937, Serial No. 163,166

18 Claims. (Cl. 101—248)

This invention relates to registering mechanism for the cylinders of printing machines, and is particularly adapted for use with that type of printing machine wherein several impressions are made in sequence, as for instance, a multi-color printing machine. More particularly, the invention relates to a mechanism for rotatively and axially adjusting a form cylinder to accurately register the printing, and which is operable to make such adjustments while the machine is in operation.

One object of the invention is to provide an improved registering mechanism for a printing machine operating upon a web, and which is adapted to rotatively and axially adjust a cylinder to compensate for irregularities in the register of the impressions.

Another object is to provide in a machine of the above nature a mechanism adapted to axially adjust a cylinder, in operable combination with a mechanism to rotatively adjust a cylinder, whereby one will not interfere with the adjustment made by the other and either or both may be actuated while the machine is in operation.

It is also an object of this invention to provide registering mechanism for machines operating upon a web, or webs, of generally improved construction, that will be simple, durable and inexpensive in construction, as well as convenient, practical, serviceable and efficient in its use.

With the foregoing and other objects in view, which will appear as the description proceeds, the invention resides in the combination and arrangement of parts, and in the details of construction hereinafter described and claimed.

The preferred embodiment of the invention is illustrated in the accompanying drawings, wherein:

Figure 1 is an elevational view of the combined rotative and axial cylinder registering mechanism, embodying the features of this invention;

Figure 2 is a vertical broken section taken on line 2—2 of Figure 3;

Figure 3 is a sectional view taken on line 3—3 of Figure 2;

Figure 4 is a sectional view taken on line 4—4 of Figure 2;

Figure 5 is a detail view of a portion of the mechanism as seen in the direction of arrow 5 of Figure 4;

Figure 5A is a detail view of a modification of the mechanism of Figure 5;

Figure 6 is a vertical section through the axial registering mechanism; and

Figure 7 is an end view of the axial registering mechanism.

Referring now to the drawings, the reference numeral 11 indicates a form cylinder of a printing or other machine adapted to operate upon a web and which during such operation may require axial as well as rotative adjustment relatively to the web and to a cooperating cylinder not shown, to register printed impressions being imposed upon the web. The cylinder 11 is journaled in spaced apart machine frames 12 and 13, upon which the rotative adjusting mechanism and the axial adjusting mechanism are respectively mounted. The cylinder 11 has shaft extensions 14 and 15 oppositely directed from its ends which may be journaled in roller bearings 10 (Figure 2) and 62 (Figure 6) respectively.

A helical adjustable gear composed of two sections 16 and 17, and having backlash eliminating means incorporated therein, is drivingly connected to the shaft extension 14 in a manner to be hereinafter described and this gear may be driven by a gear 18 in timed relation with the machine, it being understood that the gear 18 is operably associated with the machine drive.

The driving connection between the shaft extension 14 and the composite gear 16, 17 includes a hub member 19 which is secured to the shaft 14 by a key 21 and a plate 20 secured to the end of the shaft 14 by screws 20'. The hub member 19 is provided with oppositely directed radial arms 22 and 23 (Figures 2 and 4) having a plate 24 secured to the peripheral face of each by screws 25. The gear sections 16 and 17 are held together by a plurality of screws 26. The gear section 17 is recessed in its face opposing the section 16 as at 27 and plates 28 are secured upon the inner surface of an annular wall 29 formed by the recess 27. The arms 22 and 23 are extended into the recess 27 to dispose the plates 24 thereon into close proximity with the inner face of the wall 29. The plates 28 are circumferentially spaced from the plates 24, each plate 24 having an inclined edge 31 opposing an inclined edge 32 on the respective plate 28. A plate 33 secured on each of an opposing pair of radial arms 34 of a spider frame 35, is disposed between each pair of plates 24 and 28. The plate 33 has an inclined edge 36 in abutment with the inclined edge 31 of the plate 24 and an inclined edge 37 in abutment with the inclined edge 32 on the plate 28.

To insure that the gear 16, 17 is securely drivingly connected by the plates 24, 28 and 33, a pair of springs 38 and 39 are provided, each of which reacts between a post 40 provided on the

gear section 17 and a shoulder 41 provided on each of the arms 22 and 23 of the hub member 19. The springs 38 and 39 constantly urge the gear section 17 rotatively with respect to the hub member 19 so that the plate 33 will be clampingly engaged by and between the plates 24 and 28. From the above construction, it will be obvious that movement of the plate 33 axially with respect to the shaft 14 will rotate the gear 16, 17 relatively to the shaft 14, the direction of rotation being dependent upon the direction of such axial movement, whereby the cylinder 11 may be rotatively adjusted with respect to a cooperating cylinder to register therewith.

15 The arms 34 of the spider frame 35 extend through openings 30 provided in the end face of the gear section 16 from a hub 42 which is suitably journaled as by a ball bearing 43 to a stud shaft 44. The stud shaft 44 is supported by a bracket 45 secured to a bracket 46 by bolts 47 and the bracket 46 is connected to a sleeve 40a which slides in frame 12, by bolts 48. The shaft 44 is secured against rotation in the bracket 45 by a key 50. The outer end of the stud shaft 44 is threaded as at 49 and a manually operable nut 51 may be provided and internally threaded as at 52 to cooperate with the threaded shaft end 49 to move the spider frame 35 axially in either direction as desired, whereby through the arms 34 the plate 33 will be moved axially with respect to the shaft 14 to rotatively adjust the gear 16, 17 relatively to the hub member 19 and cylinder 11. When it is desired to manipulate the spider frame 35 from a remote position, a gear 53 may be substituted for the nut 51 which gear may be arranged to be rotated in either direction by a motor, not shown, in a well known manner under control of an operator remotely stationed, as for instance, at the delivery end of the machine.

40 In order to prevent possible distortion or twisting of the arms 34 of the spider frame 35, arcuately formed shelves 54 are provided extending from the gear section 16. The shelves 54 extend outwardly from the outer face of the gear section 16 in radial alignment with each of the arms 34 of the spider frame 35, the arms 34 being each provided with an arcuately formed boss 55 adapted to slidily rest upon the respective shelf 54. Herein the spider frame 35 is shown provided with 50 four arms. Two of these arms 34 which are diametrically opposite, enter the gear section 16 and have the plates 33 secured thereto. The other diametrically opposed arms 34' do not enter the gear section 16 and are not provided with 55 plates 33, but all of them engage shelves 54 whereby the frame 35 is rigidly maintained concentric with the cylinder 11. The inclined surfaces 31 and 36 are arranged so that the tendency is to constantly urge the plate 33 axially away from the 60 bracket 45 and toward the cylinder 11 under action of the springs 38, 39.

The axial adjusting mechanism, (see Figures 6 and 7) is associated with the shaft extension 15 and includes a sleeve 61 slidably supported in the 65 frame 13, and which holds the roller bearing 62, in which the shaft 15 is journaled and a bracket 63 which is secured to the sleeve 61 by screws 64, and secured to and journaled on a stud shaft 65 by ball thrust bearings 66 and 67. The shaft 65 is 70 provided with a threaded end 68 and is supported by a bracket 69 secured to the frame 13 by screws 71.

The shaft is secured to the bracket 69 against rotation by a key 72. A manually operative nut 75 73 is provided with internal threads 74 adapted to

cooperate with the threaded end of the shaft 65 to move the same and with it the cylinder 11 axially, to adjust the cylinder into correct axial register with a cooperating cylinder of the machine. As in the previously described rotative registering mechanism, a gear 70 may be substituted for the nut 73 to be driven by a motor, not shown, which may be controlled from a remote station to cause rotation of the gear 70 in either direction.

The shaft 65 is provided with an annular shoulder 75 facing the nut 73 and which engages a disc 76 mounted on the shaft 65. A plurality of springs 77 are provided which react between the disc 76 and the bracket 69 to maintain the nut 73 tightly against the bracket 69, whereby rotation thereof will cause axial movement of the shaft 65 and with it the cylinder 11.

In machines of the above nature, the gearing including the composite gear 16, 17, and the gear 18 are preferably provided with helically cut teeth to insure more efficient and smooth operation. In such instances, when the cylinder 11 is moved axially, it also moves rotatively due to the cooperating screw-like action between the meshed teeth on the gear 16, 17 and gear 18, hence rotative readjustment is required. Such a disadvantageous result is prevented in the combined mechanisms of this invention by the use of the inclined cooperating edges 31, 36 and 32, 37 of the plates 24, 28 and 33 respectively, and the determined angle of inclination of these edges.

In order to avoid any rotative movement of the cylinder when it is moved axially, the sum of the angles of the inclined edges 31, 32, 36 and 37 is substantially equal to the angle of the helical teeth on gear 16, 17 and the direction of the rotative movement induced by these edges is reverse to that caused by the gear teeth. This arrangement is indicated in the drawings wherein the dotted line shown in Figure 1 represents the cooperating inclined edges 31, 36 and 32, 37 and the full lines indicate the angle and direction thereof of the teeth of the gear 16, 17. Figure 5 also illustrates this arrangement by dotted lines representing a tooth of the gear 16, 17 and the full lines the 40 inclined edges 31, 32, 36 and 37. By this arrangement, any rotative movement induced by the axial movement of the cylinder is compensated for by the cooperating inclined edges and no rotative readjustment is required whenever the cylinder is 50 axially adjusted, as is usually the case when other axially adjusting devices are used in connection with helical gears. Referring to Figure 5A, it will be obvious that the same effect would be produced if the angle of the cooperating inclined edges 85 55 and 87, shown therein in place of the inclined edges 31 and 36, depicted in Figure 5, was made equal to the helical angle of the gear teeth and straight line edges 86 and 87 were provided in 60 place of the inclined edges 32 and 37, shown in Figure 5.

In order that the relative position of cylinder 11 to other parts of the machine may be readily ascertained, and also as a guide to the extent of movement when either rotary or axial adjustments of the cylinder are made, indicating devices are provided on each of the adjusting mechanisms. The device for indicating the position of the cylinder rotatively, consists of a disk 78 (Figure 2) secured to the nut 51, by any convenient 70 means and suitably calibrated. A cooperating index member 79 is secured to the bracket 45. A similarly calibrated disk 81 (Figure 6) is secured to the nut 73 and a similar index member 82 is secured to the bracket 69, and it will be under- 75

stood that these members serve to indicate the position of the cylinder 11 in respect to its axial adjustment in the frame.

The above described combined rotative and axially registering mechanism provides a simple and inexpensive means for registering the form cylinder of a printing machine whereby the printed matter may be conveniently and accurately maintained in register and whereby the printed matter may be brought into register while the machine is in operation. By means of this mechanism, a cylinder may be axially adjusted without interfering with the rotative adjustment and vice versa due to the provision of the above described compensating arrangement. By the spring means described and illustrated, backlash is effectually eliminated when making either axial or rotative adjustments.

It will be understood that the invention may be embodied in other specific forms without departing from the spirit or essential attributes thereof, and it is therefore desired that the present embodiment be considered in all respects as illustrative and not restrictive, and it will be further understood that each and every novel feature and combination present in or possessed by the mechanism herein disclosed forms a part of the invention included in this application.

What I claim is:

30 1. In a machine having a cylinder mounted for rotation, a driving gear, a driven gear supported with the cylinder and meshing with the driving gear, and means operably interposed between the driven gear and cylinder to bias the driven gear towards angular movement relative to the cylinder, and means operable from a point external of the cylinder and operable in opposition to the said biasing means to rotatably adjust the cylinder relative to the said driven gear.

40 2. In a machine having a cylinder mounted for axially sliding and rotating movements, driving means for said cylinder including meshed first and second helical gears, mechanism to axially adjust said cylinder and first helical gear relatively to the second helical gear, and means operatively interposed between said cylinder and said first helical gear to rotatively urge said cylinder equally and oppositely to any rotation thereof induced when the cylinder and first helical gear are axially adjusted relatively to said second gear.

45 3. In a machine having a cylinder mounted for axially sliding and rotating movements, driving means for said cylinder including a pair of meshed helical gears, mechanism to axially adjust said cylinder and a first one of the gears relatively to a second one of said gears, mechanism to rotatively adjust said cylinder relatively to the first gear including connecting members operably interposed between said cylinder and the first gear, 50 said connecting members being operable to rotatively urge said cylinder equally and oppositely to any rotation thereof induced when the cylinder and first gear are adjusted by said axially adjusted mechanism.

55 4. In a machine having a cylinder mounted for adjustment by axially sliding and rotating movements, a first helical gear adjustably secured to said cylinder with its axis in alignment therewith, a second helical gear in mesh with the first gear and being fixed against axial movement, cooperating members operably interposed between said cylinder and said first gear to drivingly connect the same and being operable to rotatively urge the cylinder equally and oppositely to any rota-

tive movement induced by axially adjusting said cylinder and first gear.

5 5. In a machine having a cylinder mounted for adjustment by axially sliding and rotating movements, a gear mounted with its axis in alignment with said cylinder, cooperating members operably interposed between said cylinder and said gear to drivingly connect the same including a member on said gear, and a member operatively connected to said cylinder, said members having cooperat- 10 ing inclined edges.

15 6. In a machine having a rotatable cylinder, a gear mounted with its axis in alignment with said cylinder and having helical teeth, cooperating members operably interposed between said cylinder and said gear to drivingly connect the same including cooperating members having abutting inclined edges the total angle of inclination of which is substantially the same as the angle of inclination of the teeth on said gear. 20

25 7. In a machine having a rotatable cylinder, driving means for said cylinder including a gear mounted to rotate relatively to said cylinder, and a driving connection between said cylinder and said gear including a first plate operatively connected to said cylinder, a second plate connected to said gear, and an axially slid able third plate having an inclined edge abutting and cooperating with an inclined edge on one of the other plates whereby axial movement of said third plate will 30 relatively rotate said gear and said cylinder.

35 8. In a machine having a rotatable cylinder, a shaft extending from said cylinder, a hub member on and secured to said shaft, a gear rotatably mounted on said hub member, a first member on 35 said hub member, a second member on said gear, an axially slid able third member disposed between said first and second members in abutment with each and having an inclined surface co-operating with an inclined surface formed on one of the other members, and a spring reacting between said gear and said hub member to maintain said first and second members in engagement with said third member. 40

45 9. In a machine having a rotatable cylinder, a shaft extending from said cylinder, a hub member on and secured to said shaft, a gear rotatably mounted on said hub member, a first member on said hub member, a second member on said gear, an axially slid able third member disposed between said first and second members in abutment with each and having an inclined surface co-operating with an inclined surface formed on one of the other members, a spring reacting between said gear and said hub member to maintain said first and second members in engagement with said third member and means to slide said third member axially with respect to said gear to rotate the gear relatively to said cylinder. 50

55 10. In a machine having a rotatable cylinder, a gear for driving said cylinder, and means to rotatively adjust said gear relatively to said cylinder including a part operatively connected to said cylinder, a part operatively connected to said gear, one of said parts having an inclined surface, and an axially slid able member having an inclined surface cooperating with the inclined surface on said part, disposed between said parts. 60

65 11. In a machine having a rotatable cylinder, a helical gear for driving said cylinder, and means to rotatively adjust said gear relatively to said cylinder including a part operatively connected to said cylinder, a part operatively connected to said gear, one of said parts having an inclined surface, and an axially slid able member 70

75

having an inclined surface cooperating with the inclined surface on said part, disposed between said parts, said inclined surfaces being inclined reversely to the inclination of the helical teeth 5 of said gear.

12. In a machine having a rotatable cylinder, an axially fixed first helical driving gear, a second helical gear in mesh with said first helical gear, a first means to axially move said cylinder and second gear, and a second means 10 adapted to be moved axially to angularly adjust said cylinder and said second gear relatively to each other, said second means being adapted, when held against axial movement, to cause relative angular movement of predetermined amplitude between said cylinder and said second gear when they are moved axially to maintain the said gear angularly stationary.

13. In a machine having a rotatable cylinder, 20 a helical gear for driving said cylinder, and means to rotatively adjust said gear relatively to said cylinder including a part operatively connected to said cylinder, a part operatively connected to said gear, both of said parts having an inclined 25 surface, and an axially slidble member disposed between said parts and having an inclined surface at each end cooperating with the inclined surfaces on the parts adjacent each end, the sum of the angles of said surfaces being substantially equal to the helical angle of the teeth of 30 said gear.

14. In a printing machine, a rotatable member 35 movable axially, a helical gear held on the member and prevented from axial motion with respect thereto, a helical driving gear in mesh with the gear on the member and held against axial motion, and means to rotate the first mentioned gear with respect to the member while the machine is running.

15. In a printing machine, a rotatable member 40 movable axially, a helical gear held on the member and prevented from axial motion with respect thereto, a helical driving gear in mesh with the gear on the member and held against axial motion, and means to rotate the rotatable member with respect to the first mentioned gear when the member and the first mentioned gear are moved axially relative to said helical driving gear, the amplitude of the said rotative move- 45

ment of the rotatable member relative to the first mentioned gear being equal and opposed to the rotative movement that would be imparted to the rotatable member by the axial movement of the first mentioned helical gear relative to 5 the said helical driving gear to thereby avoid rotational movement of the member when it is so moved.

16. In a printing machine, a rotatable member 10 movable axially, a helical gear held on the member and prevented from axial motion with respect thereto, a helical driving gear in mesh with the gear on the member and held against axial motion, and means to rotate the member with respect to the first mentioned gear while the member is axially stationary.

17. In a printing machine having a form cylinder mounted for adjustment axially and rotatively, a gear mounted in axial alignment with said cylinder and held against axial movement 20 with respect thereto, and driving means connecting said cylinder and said gear, including adjustable means adapted to rotate the gear in one direction with respect to the cylinder and resilient means tending to rotate the gear in the 25 opposite direction, to prevent backlash in the driving means.

18. In a printing machine having a form cylinder rotatably supported in a bearing and adjustable axially and rotatively, a gear mounted 30 in axial alignment with said cylinder and held against axial movement with respect thereto, co-operating members drivingly connecting said cylinder and said gear including adjustable means connected to the cylinder and the gear and 35 adapted to rotate the gear in one direction with respect to the cylinder, first resilient means connected to the cylinder and the gear and tending to rotate the gear in the opposite direction, other adjustable means adapted to move the bearing 40 and thereby the cylinder axially in one direction, and second resilient means tending to move the bearing and thereby the cylinder in the opposite direction; said first and said second resilient means acting to prevent backlash of 45 the cylinder axially and rotatively.

WILLIAM F. HUCK.
